UNITED STATES PATENT OFFICE.

HAROLD ROWNTREE, OF CHICAGO, ILLINOIS, ASSIGNOR TO NATIONAL PNEUMATIC COMPANY, OF CHICAGO, ILLINOIS, A CORPORATION OF WEST VIRGINIA.

DOUBLE-DECK CAR.

1,111,971.

Specification of Letters Patent. Patented Sept. 29, 1914.

Application filed April 4, 1912. Serial No. 688,385.

To all whom it may concern:

Be it known that I, HAROLD ROWNTREE, a citizen of the United States, residing at Chicago, county of Cook, State of Illinois, 5 have made a certain new and useful Invention in Double-Deck Cars, of which the following is a specification.

The object of the invention is to provide a double deck car which is simple in construction and efficient in operation, and wherein the carrying capacity is greatly increased, while at the same time provision is made for the prepayment of fares as passengers enter the car.

15 A further object of the invention is to provide a double deck car structure with a stairway connecting the lower and upper decks which stairway arrangement is made shiftable, whereby the prepayment of fares 20 may be effected from entering passengers and as they enter whether the entry way for passengers is on one side or the other of the car.

A further object of the invention is to 25 provide a double deck car of the prepayment type, wherein entrance to the car body from the street is accomplished through the sides of the car intermediate the ends thereof, at which point the fare prepayment arrangement is also provided, as well as a 30 stairway leading from the lower deck of the car to the upper deck thereof.

Other objects of the invention will appear 35 more fully hereinafter.

35 The invention consists substantially in the construction, combination, location and relative arrangement of parts, all as will be more fully hereinafter set forth, as shown in the accompanying drawings, and finally 40 pointed out in the appended claims.

Referring to the accompanying drawings, and to the various views and reference signs appearing thereon—Figure 1 is a view in top plan, somewhat diagrammatic, showing 45 the floor plan of the upper deck of a double deck car embodying the principles of my invention. Fig. 2 is a similar view showing the floor plan of the lower deck or floor of the car. Fig. 3 is a view on a larger scale, 50 parts broken off, showing in top plan the arrangement of floor plan of the upper deck of the double deck car at and in the vicinity of the upper deck landing of the stairway leading from the lower to the upper deck.

Fig. 4 is a broken view in vertical section 55 on the line 4, 4, Fig. 5, looking in the direction of the arrows. Fig. 5 is a broken view in horizontal section, on the line 5, 5 Fig. 4, looking in the direction of the arrows. Fig. 6 is a view in elevation, parts in vertical sections showing an arrangement of door operating mechanism employed in connection with a double deck car embodying the principles of my invention. Fig. 7 is a view in top plan, somewhat diagrammatic, 65 parts being broken off, and parts in section, showing the arrangement of motor mechanism as employed in Fig. 6 and the controlling arrangement therefor.

The same part is designated by the same 70 reference sign wherever it occurs throughout the several views.

In accordance with the principles of my invention, I propose to provide a double deck car, and especially a car having a center entrance, that is, an entrance through the sides of the car at a point intermediate its ends. I also propose to apply to such a car an arrangement inside the entry ways or doorways thereof for the prepayment of 80 fares of entering passengers as they enter. I also propose to employ a double ended car having entry openings at each side at points intermediate the ends of the car, and preferably at the center of the length of the car. I also propose to make the car a double deck 85 car so that the entry of passengers to either the lower or the upper deck is accomplished through the same center side doorway and through the same fare prepayment arrangement at the point of entry, whereby the carrying capacity of the car may be increased doubly, while at the same time employing the fare prepayment feature. In the case of a double deck car of the character and nature referred to, I propose to employ a stairway leading from the lower deck to the upper deck of the car for the purpose of permitting passengers to ascend to or descend from the upper deck of the car, and on each 90 deck of the car I propose to provide a seating arrangement for the accommodation of passengers. It is obvious that any form of seating arrangement may be employed on either of the decks of the car for the accommodation of passengers. In Fig. 1, I have shown a simple arrangement of seats for the 95 upper deck which is well adapted for the 100 105

purpose, and wherein cross or transverse seats are employed throughout the length of the car on each side thereof, with a center aisle between them. Similarly, on the lower 5 deck any form of seating arrangement may be employed. In Fig. 2, I have shown cross seats and also longitudinally arranged seats, particularly in the vicinity of the center side doors and circularly arranged seats at the 10 ends of the car. At its ends, the car on the lower deck is provided with a somewhat circular arrangement of seats for passengers. Each extreme end of the car on the lower deck is provided with a space or 15 compartment for the accommodation of the motorman, so that the motorman may be stationed at either end of the car. This motorman's compartment is or may be separated by a partition wall from the body of the car.

20 Access to or egress from the motorman's compartment at the ends of the car may be secured through a doorway located in any convenient position relatively to the motorman's compartment.

25 Any suitable arrangement of doors may be employed for the center side doorways and they may be operated either manually or by power mechanism, as may be desired. In accordance with the fare prepayment arrangement the control of the center side doors is effected in accordance with the principles of my invention from the fare prepayment point inside of the car.

In accordance with my invention I propose to associate the conductor's station, at the fare prepayment point, in convenient relation with reference to the frame work for the stairway leading from the lower to the upper deck of the car. Where the car is 35 provided at its center with doorways on each side thereof, I prefer to employ a turret arrangement or rotatable construction for the stairway and its framing and the conductor's stand, so that when the doorway 40 at one side of the car is employed as the entry way into the car, the stairway leading to the upper deck will be positioned on the opposite side of the car, and where the opposite entry doorway is employed the entire 45 stairway framework is revolved about a vertical central axis as in the manner of a turret, so as to be shifted to the opposite side of the car, as indicated in full and dotted lines in Fig. 5.

50 Referring now more in detail to the drawings, reference sign A designates the lower deck floor of the car.

B designates the upper deck floor of the car. Located at the center of the car, on 60 each side thereof, are doorways which are controlled by doors indicated at C, D. As above indicated, these doors may be of any suitable construction or arrangement, and may be operated or controlled in any suitable manner, either manually or by power

mechanism. In the particular form shown, to which, however, my invention, as defined in the claims, is not to be limited or restricted, folding doors are employed. When the doorway on one side of the car is employed 70 for the entrance and exit of passengers, those on the opposite side of the car are to be maintained closed. Opposite the doorway in the sides of the car I arrange the stair casing, indicated generally at F, by means 75 of which passengers may ascend to, or descend from, the upper deck, after entering the car through the center side doorway at the lower deck of the car. Where a turret form of construction is employed the stair framework is suspended from a turn table section E, which is circular in contour and which constitutes part of the flooring of the upper deck B. A suitable opening is provided through the turn table E, for the entrance and exit of passengers therethrough 80 when going to or from the upper deck and the stairway, as clearly indicated in the drawing. Except for this passageway 85 which, if desired, may be bounded on the upper deck of the car by suitable railings G, the upper surface of the turn table E, is in the same plane with the surface of the floor B. If desired, the turn table section E, may be supported upon ball bearings indicated 90 at H, (see Fig. 4). Thus, in effect, a circular track way is formed in the floor B, of the upper deck of the car, on or in which circular track way the turn table E rests at 95 its peripheral edge so as to be capable of freely rotating. The stair and its framing are supported or suspended from this turn table E. Also supported from this turn table E or carried by the stairway framing 100 is a frame indicated at J, which constitutes the conductor's station on the lower deck of the car. This conductor's station includes a seat K, for the conductor, and a table or platform L, in front of the seat K, which may be conveniently used by the conductor as a 105 table upon which or across which change, transfers, and other operations may be conducted. The framework of the stairway, which constitutes a turret or turn table structure, is preferably provided with a central vertical pintle indicated at M, which is stepped into a seat formed to receive the same in the center of the floor A of the lower deck of the car, as clearly indicated in 110 Fig. 4, thus constituting a pivot pintle about 115 which the turret may turn. Depending from the floor section E of the turn table structure are posts N, constituting parts of the turret structure and upon which the steps or stairway are supported and which afford convenient hand holds for passengers. One of these vertical standards or posts may be provided with a locking catch, indicated 120 at O, (see Fig. 4), for engagement with a corresponding seat in the floor A, of the 125 130

lower deck of the car to hold the turret in its proper position when revolved. It will be observed that the seat and station of the conductor is located opposite approximately 5 the midwidth of the side doorway. With this arrangement as passengers enter through the doorway they are required to pass the conductor, on the way to either end of the car on its lower deck, or to the 10 stairway leading to the upper deck, and consequently thus affording the conductor the opportunity of collecting the fares of the passengers as they enter to whichever part of the car the passenger may proceed after paying 15 his fare. The turn table E constituting part of the flooring of the upper deck of the car may be provided with a seat section indicated at P, (see Figs. 1 and 3), arranged opposite the opening for entryway to and 20 from the stairway.

As above indicated the doors may be controlled either manually or by power mechanism. In either event the controlling means for the center side doors may be controlled 25 from the conductor's station. A convenient arrangement for accomplishing this is shown wherein the conductor's station is equipped with a foot treadle or push button, indicated at R, located in convenient position 30 for the conductor while occupying his fare prepayment station, to effect the operation or control of the door movements. Where doorways are provided on each side of the car, and the revolving turret arrangement 35 is employed, it will be understood that a similar control is effected of the doors on each side of the car. In this case the foot treadle or push button R, will be carried around with the turret when it is shifted 40 to carry the stairway from one side of the car to the other, and when the turret is in position to utilize the center side doorway on one side of the car the push button or treadle R, will be brought into coöperative 45 relation for controlling the door movements on that side of the car, and when the turret is rocked or revolved around into position to use the center side doorway on the opposite side of the car the foot treadle will 50 then be brought into coöperative relation with door controlling devices for controlling the doors on the opposite side of the car. Thus the turn table carries the foot treadle, or other operating connection or means, 55 which is shiftable with the turret into position to control the side doors on one side or the other according to the position of the turret. In any case the control is effected from the conductor's station so that the conductor 60 is enabled to operate the doors, whether on one side of the car or the other, without leaving his station for that purpose. In this way the control of the entry and exit of passengers is effected under the personal 65 control and supervision of the con-

ductor, thereby avoiding accidents to entering or boarding and alighting passengers.

The door mechanism employed, if power operated devices are used, may be of any suitable or convenient form. I have shown a simple arrangement wherein a power cylinder indicated at S, is employed and which is controlled by the conductor from the fare prepayment station and through suitable connections to the doors for effecting or controlling the operation of the latter. Such control connections are indicated at s, for one side of the car and at t for the other side of the car. When the turret is in one position the treadle R is brought into coöperative relation with respect to the door control mechanism s, and when shifted into its other position the treadle is brought into coöperative relation with respect to the control mechanism t. The locking device O, serves to hold the stairway turret in its proper position. Of course it is obvious that the upper deck of the car may be roofed over if desired, or it may be left open. It is obvious that either end of the lower deck of the car may be used as a smoking compartment, or the upper deck may be used for that purpose.

The station for the motorman is at the end 95 of the car on the lower deck. For this purpose a compartment, indicated at W, may be provided at each end of the car, and separated from the interior of the car by a suitable partition V. A door for the ingress or egress of the motorman to and from this compartment may be provided. I have shown such a door at the extreme end of the car, as indicated at V, but it is obvious that this door may be located at any convenient point.

If desired suitable back rests X may be provided on the upper deck, which back rests are curved concentric with the axis of revolution of the turn table E, so as to coöperate with the seat section P, carried by the turn table, whether said seat section is at one side or the other side of the car.

Having now set forth the objects and nature of my invention, and a construction embodying the principles thereof, what I claim as new and useful, and of my own invention, and desire to secure by Letters Patent is,—

1. In a double deck car, a doorway for the ingress or egress of passengers to and from the lower deck of the car; a door therefore, a stairway leading from the lower to the upper deck of the car, and means located adjacent said stairway for controlling the door movements.

2. In a double deck car, a center doorway in the side of the lower portion of the car, a stairway located inside the car opposite said doorway and leading to the upper deck,

- a door for the center side doorway, and means located adjacent the stairway for controlling said door.
3. In a double deck car, a doorway at each side of the lower portion of the car, a stairway leading from the lower to the upper deck of the car and when in position for use located inside the car opposite one of said doorways, and means for shifting said 10 stairway into position opposite the other doorway, whereby either of said doorways may be used.
4. In a double deck car, a doorway for the ingress or egress of passengers to and from the lower deck of the car, a door for the doorway, a stairway leading from the lower to the upper deck of the car, the lower deck landing of the stairway being positioned opposite the doorway, and means 20 located adjacent the lower deck landing of the stairway for controlling the movements of said door.
5. In a double deck car having a doorway, a stairway located within the car, opposite the doorway, a conductor's stand carried by 25 the stairway framework adjacent the lower deck landing thereof, a door for said doorway, and means located adjacent the conductor's stand for controlling the operation 30 of the door.
6. In a double deck car having doorways in opposite sides thereof, a turn table, a stairway supported by the turn table and leading from the lower to the upper deck of the car, the lower deck landing of the stairway being 35 positioned opposite one of said doorways when in position for use, whereby shifting said turn table, said lower deck landing of the stairway may be brought into position 40 opposite the other of said doorways.
7. In a double deck car having doorways in the opposite sides thereof, a turn table, a stairway supported thereby, the lower deck landing of the stairway adapted to be 45 brought opposite the doorway in one side or the other of the car, according as said turn table is shifted, doors for said doorways and means for controlling said doors.
8. In a double deck car having doorways 50 in the opposite sides thereof, a turn table, a stairway supported thereby and leading from the lower to the upper deck of the car, the lower deck landing of the stairway adapted to be brought opposite one or the 55 other of the doorways in the side of the car according as the turn table is shifted from one position to another, doors for said doorways and means located within the car for controlling the operation of said doors.
- 60 9. In a double deck car having doorways in the opposite sides thereof, a turn table, a stairway carried thereby and leading from the lower to the upper deck of the car, the lower deck landing of the stairway adapted 65 to be brought into position opposite one or the other of said side doorways according as the said turn table is shifted into one position or another, doors for said doorways and means located adjacent said stairway lower deck landing for controlling the operation 70 of the doorway.
10. In a double deck car having doorways in the sides thereof, a turn table, a stairway carried thereby and leading from the lower to the upper deck of the car, said turn table 75 adapted to be shifted into position for the lower deck landing of the stairway to be brought opposite one or the other of said side doorways and means for locking the turntable in its shifted position. 80
11. In a car having doorways in the opposite sides thereof, a door for each doorway, a conductor's stand arranged intermediate said doorways, a support for said stand, said support being reversible relative to said 85 doors and doorways, whereby said stand may be shifted into position to face either of said doors and doorways.
12. In a car having doorways in the opposite sides thereof, a door for each doorway, 90 a conductor's stand arranged intermediate said doorways, a support for said stand, said support being reversible relative to said doors and doorways whereby said stand may be shifted into position to face either of 95 said doors and doorways, and means for locking said support in either position.
13. In a car having doorways and doors in the opposite sides thereof, a conductor's stand arranged intermediate said doorways, 100 a support for said stand, said support being reversible whereby said stand may be shifted into position to face either of said doors and doorways; doors for said doorways and means arranged adjacent the conductor's 105 stand for controlling said doors.
14. In a car having doorways in the opposite sides thereof, a conductor's stand arranged intermediate said doorways, a support for said stand, said support being reversible whereby said stand may be shifted into position to face either of said doorways, doors for said doorways, independent means for operating the doors on opposite sides of the car, and means associated with the conductor's stand to coöperate with the door controlling means on one side of the car or the other according to the position into which the conductor's support is shifted. 115
15. In a double deck car having doorways 120 in the opposite sides thereof, a stairway leading from the lower to the upper deck of the car and located intermediate said doorways, said stairway being movable whereby it may be shifted into position for the lower 125 deck landing thereof to face either of said doorways.
16. In a double deck car having doorways in the opposite sides thereof, a stairway arranged intermediate said doorways and lead- 130

ing from the lower to the upper deck of the car, said stairway being movable whereby it may be shifted into position for the lower deck landing thereof to face either of said doorways, and means for locking said stairway in either position.

17. In a double deck car having doorways in the opposite sides thereof, a stairway arranged intermediate said doorways, and leading from the lower to the upper deck of the car, said stairway being movable whereby it may be shifted into position for the lower deck landing thereof to face either of said doorways, doors for said doorways and means associated with the movable stairway for controlling said doors.

18. In a double deck car having doorways in the opposite sides thereof, a stairway arranged intermediate said doorways and leading from the lower to the upper deck of the car, said stairway being movable whereby the lower deck landing thereof may be shifted into position to face either of said

doorways, and a conductor's stand carried by said stairway.

19. In a double deck car having doorways in the opposite sides thereof, a stairway arranged intermediate said doorways and leading from the lower to the upper deck of the car, said stairway being movable whereby it may be shifted into position for the lower deck landing thereof to face either of said doorways, doors for said doorways, a conductor's stand carried by said stairway and means associated with the conductor's stand for controlling the doors on one side or the other of the car, according to the position occupied by the stairway.

In testimony whereof I have hereunto set my hand in the presence of the subscribing witnesses, on this 29th day of March A. D., 1912.

HAROLD ROWNTREE.
